UNITED STATES PATENT OFFICE.

FRANK KEIPER, OF ROCHESTER, NEW YORK.

INTERLOCKING MECHANISM.

No. 802,865.

Specification of Letters Patent.

Patented Oct. 24, 1905.

Application filed February 25, 1904. Serial No. 195,264.

To all whom it may concern:

Be it known that I, FRANK KEIPER, a citizen of the United States, residing at Rochester, in the county of Monroe and State of New York, have invented certain new and useful Improvements in Interlocking Mechanisms; and I do hereby declare the following to be a full, clear, and exact description of the invention, such as will enable others skilled in the art to which it appertains to make and use the same.

Reference is had to the accompanying drawings, forming a part of this specification, and to the reference-numerals marked thereon.

My present invention relates to an improvement in interlocking mechanism such as is described in the pending application of A. J. Gillespie, Serial No. 113,686, and has for its purpose increasing the accuracy and strength of the interlocking system described therein.

The invention consists of details by which these improvements are embodied, the patentable features being pointed out in the claims at the end of this specification.

In the drawings, Figure 1 represents a part of the keyboard of a voting-machine, showing the rear portion of the keys and the interlocking straps with the wedges connected thereto. Fig. 2 shows a cross-section of the interlocking channel with the wedges and 40 interlocking blocks in position. Figs. 3 and 4 are perspective views of the interlocking straps and wedges; and Figs. 5 and 6 show the form of the interlocking block that is preferably used in connection therewith, which interlocking block constitutes the principal feature of this invention.

Similar reference-numerals in the different figures indicate similar parts.

The parts herein described have been illustrated, preferably, in connection with the parts of voting-machines, such as are described in the Gillespie application above referred to, or in connection with the parts illustrated, for example, in the Gillespie patent No. 647,657, patented April 17, 1900, and may be used in connection with that kind of a machine, either of the vertical type or of the horizontal type, or any of the voting-machines patented thereafter, although it is obvious that the invention is also adapted to any other form of voting-machine to which this method of interlocking might be applicable.

In Fig. 1 the parts marked 1 represent the voting-keys. 2 refers to the interlocking

straps, to the end of which are connected the wedges 3 and 4, which wedges nest together when in unvoted position, the straps thereof inclosing an interlocking block between them.

The form of the interlocking block I preferably employ is shown in Figs. 5 and 6, referred to by the reference-numerals 5 and 6, said blocks consisting of a thick portion (marked 7) having the interlocking surfaces, which are comparatively narrow, said portion of the block being stiffened and strengthened by a web, (marked 8,) which extends upward therefrom. The block may be made in a single piece, as is indicated in Fig. 6, or in a double piece, as is indicated in Fig. 5, the purpose of the block shown in Fig. 5 being to provide room for a grouping-pin to pass between the two halves thereof for the purpose of holding said block against movement in either direction past the grouping-pin. The block shown in Fig. 5 may be made all in one piece, in which the web or the flange thereof may be made even thinner than what is indicated therein. The object of the shape of this block may be described as follows: In previous experiments interlocking rollers have been used instead of the blocks. The size of said rollers is necessarily limited to their diameter, and in the effort to get the machine as small as possible, (which experience has shown to be preferably an inch and a quarter between centers of office-lines,) such rollers in an eight or nine party machine must necessarily have a very small diameter and be correspondingly weak—too weak, in fact, to resist the bending strains that may be thrown on them when the whole force or leverage of a straight-ticket key is thrown upon a single key. Consequently flat blocks having a considerable width have been resorted to, such as are described in the Gillespie patent and application above referred to, it being necessary to secure this depth or width in the block to resist a bending strain that may be thrown upon said block in extreme cases. Increasing the width of said block correspondingly increases the surface which is necessarily exposed to the interlocking strap, and it has been found by experiment that the interlocking system works best when these surfaces are reduced to the fewest possible number, as is described in my copending application, and is further improved when the amount of surface exposed in each contact is reduced to a minimum. This arises from the fact that two ordinary

surfaces of metal will lie closer together under pressure than they will under gravity. The more true the surfaces are made of course the more intimate will the contact be under gravity or ordinary pressure and the less they will be moved into intimate contact when extraordinary pressure is applied to secure this result. It is obvious that it is easier to get the small ridge (marked 9) on the interlocking block true than it is to get the whole surface of said block if it were of the same thickness throughout as it is at its thickest part or that with the same degree of irregularity in its surface it will be more easily brought into intimate contact with its associated parts. By this is meant that degree of contact under light compression, which must exist, so that any further compression, however severe or strong, will not seriously diminish the outside measurement of a series of pieces in such compression even if the force applied be much greater than can be applied by a voter in operating the parts of the machine described in the patents above referred to. It is estimated that the maximum force on an interlocking strap that can be exercised by a voter, tending to draw the wedge connected to said strap to voted position against the resistance of the interlock, is from two hundred to four hundred pounds, and with such pressure as this applied the parts should yield as little as possible from their normal condition and be practically incompressible long before the maximum pressure is reached. This result will be secured, it is believed, from blocks of the above-described shape better than will be secured if the blocks are so shaped as to interlock over their whole surface. The thick part of the block may be rounded, so that its contact with the interlocking wedge or strap will be reduced to a line.

Having thus fully described my invention, what I claim as new is as follows:

1. A long flat interlocking block having a thick part containing the interlocking surface, and a thinner web or flange running longitudinally of said thick part for the purpose of stiffening the same to resist bending strains.
2. A long flat interlocking block the interlocking part being nearly rectangular in outline and having interlocking surfaces extending across said block and covering a small portion thereof, said block being provided with a thinner web or flange extending longitudinally across the thicker part for the purpose of stiffening the same.
3. A long flat interlocking block having interlocking surfaces extending across opposite sides thereof, said block being nearly rectangular in outline, and a thinner web or flange for the purpose of stiffening the interlocking block, said web being provided with recessed portions for securing said block in its proper position in the channel.
4. In an interlocking mechanism for voting-

machines, the combination of interlocking straps provided with wedges which nest with each other, and interlocking blocks, each interlocking block being long and flat and having a thick part to contact with said wedges and having a thin part to stiffen the block and located out of contact with said strap, whereby the contact is made wholly between the block and wedge during the operation of voting.

5. In an interlocking mechanism, the combination with the interlocking straps and wedges adapted to nest with each other, of a channel, interlocking blocks supported by said channel, said interlocking blocks having long flat portions substantially rectangular in outline on which the interlock takes place, and a thinner stiffening web or flange, said web or flange being slotted for engagement with said channel.

6. In an interlocking mechanism, the combination with straps having wedges thereon, which wedges are adapted to nest with each other, a channel having oppositely-projecting portions, and interlocking blocks supported in said channel between said straps and wedges, each interlocking block being long and flat and substantially rectangular in outline and having a tapered portion to facilitate easy engagement of the wedges therewith and also having a thinner stiffening web or flange extending longitudinally of said block, said web or flange being slotted for engagement with the opposite projecting portions of the channel.

7. A flat rectangular interlocking block, having a narrow raised interlocking surface extending transversely to the movement of the interlocking wedge.

8. An interlocking device consisting of interlocking blocks and wedges arranged alternately, said interlocking blocks being rectangular in shape and having their broad sides lying parallel to the path of movement of the wedges, said broad surfaces having a narrow raised interlocking surface extending transversely to the movement of the interlocking wedge.

9. A rectangular interlocking block extending transversely between two supporting-channels, raised interlocking surfaces on opposite sides of said block, said raised surface extending between the channels, and an extension of said block made thin to avoid interlocking contact thereon, and made wide to stiffen the block against the bending strains to which it may be subjected.

10. A thin rectangular interlocking block supported at its ends by channels, said block having a narrow thick portion, on which thick portion only it interlocks.

11. A thin rectangular block supported at its ends by channels, said block having a narrow thick portion, on which thick portion only it interlocks, the balance of the block strength-

ening the thick portion of the block against bending.

12. A thin rectangular interlocking block supported at its ends by channels, said block having a narrow thick portion, on which thick portion only it interlocks, said blocks being arranged in series with interlocking straps passed between their broad surfaces.

13. An interlocking block of rectangular outline having a raised interlocking surface extending transversely across said block and covering a narrow strip of its broad surface.

14. An interlocking block having a narrow portion, extending transversely to the movement of the interlocking wedge, made thick to confine the interlocking thereto, a wide

portion made thin to avoid interlocking contact and stiffen the thick portion.

15. A rectangular interlocking block extending transversely between two supporting channels, a raised interlocking surface on said block extending from one channel to the other, and a portion adjacent thereto made thin and wide to stiffen the block and avoid interlocking contact thereon.

In testimony whereof I affix my signature in presence of two witnesses.

FRANK KEIPER.
